UNITED STATES PATENT OFFICE

HUBERT S. MORGAN, OF SCARSDALE, NEW YORK

DESIGN FOR A MERCHANTISING DISPLAY STAND

Application filed November 25, 1932. Serial No. 46,154. Term of patent 3½ years.

To all whom it may concern:

Be it known that I, HUBERT S. MORGAN, a citizen of the United States, residing at Scarsdale, in the county of Westchester and State of New York, have invented a new, original, and ornamental Design for Merchandising Display Stand, of which the following is a specification, reference being had to the accompanying drawing, forming a part thereof.

I claim:

The ornamental design for a merchandising display stand, as shown.

HUBERT S. MORGAN.
